UNITED STATES PATENT OFFICE.

WILLIAM FELS, OF ELBERTA, ALABAMA, ASSIGNOR TO MAX NYDEGGER, OF ELIZABETH, NEW JERSEY.

MOTOR-CONTROL SYSTEM.

Original application filed July 8, 1920, Serial No. 394,678. Divided and this application filed September 3, 1921, Serial No. 498,309. Renewed December 7, 1925.

To all whom it may concern:

Be it known that I, WILLIAM FELS, a citizen of Austria, residing in Elberta, county of Baldwin, and State of Alabama, have invented an Improvement in Motor-Control Systems, of which the following is a specification.

The present invention relates to an improvement in driving mechanism for knitting machines and more particularly to automatic reversing and speed controlling mechanism, the present application being a divisional of my co-pending application Serial No. 394,678 filed July 8, 1920. One object has been to provide a machine which shall be fully or partly automatic and at the same time of relatively simple construction with a minimum of mechanically controlled and actuated parts. A further object has been to provide relatively simple means for preventing injury to the machine in case of careless or erroneous operation.

It is known that knitting machines, automatic in varying degrees, have been devised but these machines are usually of complicated design and involve a multiplicity of mechanical movements which not only make the machine expensive to manufacture, but also cause frequent breakdowns and make it necessary for the operator to devote considerable attention to repairs and adjustments.

According to the present invention, I utilize substantially the well known framework and opposed front and rear needle beds of a flat links links machine, although I do not intend to limit the application of the present invention to machines of this type, it being contemplated that the same or similar principles of operation may be applied to other types of knitting machines with suitable modifications. In connection with the flat double bed machine, I use a reciprocating carriage automatically reversible in direction and which carries with it suitable means for effecting changes in the positions of the jack actuating cams to produce corresponding changes in the stitch length, also cam positioning means for controlling the action of the needle jacks to produce either flat or links links operation according to a predetermined order, and means for engaging and disengaging a plurality of thread carriers to vary the color scheme of the fabric according to a predetermined arrange-

ment, although the device forming the subject matter of the present application will perform its functions independently of the operation of the pattern change mechanisms referred to or their equivalents.

One embodiment of my invention is illustrated in the drawings accompanying the present specification, and in which

Figure 1 is a front elevation,

Figure 2, a rear elevation,

Figure 3, a top plan view,

Figure 4, a diagrammatic representation of a portion of the electrical control system, and

Figure 5, a view in detail indicating contact mechanism mounted on a reciprocating carriage.

Referring to the drawings, a machine embodying my invention may conveniently comprise a framework A supporting a fixed rear needle bed B and a front needle bed C preferably slidable both longitudinally and transversely to separate the needle beds if desired for placing or removing the knitted fabric (Figure 3). A reciprocating carriage D is arranged above the needle beds B and C, said carriage being driven by any suitable means such as a motor E operatively connected to a drive chain 101, said chain having a slotted member 102 adapted to receive and engage the free end 103 of a lever pivotally mounted on the carriage at 104. As shown more clearly in Figures 1 and 2, the chain 101, is mounted on sprockets arranged at opposite ends of the machine, said sprockets being driven by a belt or other connection with the motor E. To effect the reciprocating motion of the carriage, means are provided for periodically reversing the direction of the current through the armature of the motor thus reversing the direction of the chain 101. To accomplish this reversing operation automatically, a reversing switch is interposed in the power circuit, said switch including as its moving member an armature 110 being controlled by a double relay, indicated at F in Figure 4 of the drawings, the opposed magnets 112 and 113 of which are alternately energized at the end of each run of the carriage, the circuit being closed through suitable contacts R and R' mounted on the framework of the machine and R'' on the carriage respectively. However, before reversing the current in

the armature of the motor, it is desirable to reduce the current or otherwise impede the movement of the carriage so as to avoid harmful impact thereof at the ends of its course. As shown in Figure 4, the motor circuit includes the conductors 105 and 106, the latter of which contains a resistance 107 and also a parallel resistance or manually operated rheostat 108. Thus, to increase the resistance in the conductor 106, the rheostat 108 may be periodically cut out. This is conveniently accomplished automatically by means of a relay including a magnet 109 and an armature 111 normally withheld from said magnet by suitable means, such as a spring 114, said magnet being in circuit with both magnets of the double relay F and also with the fixed contact R at one end of the machine, the adjustable contact R' at the opposite end of the machine, and the movable circuit closing contact R'' mounted on the carriage D. For practical purposes, the magnet 109 and the double relay may operate substantially simultaneously. However, the action of the double relay may be effectively delayed by making the bar or armature 110 thereof heavier than the bar 111 or otherwise temporarily delaying or yieldingly impeding the movement of said bar 110. Thus, the current in the motor E will be reduced either simultaneously with or just before the change of direction of the current therein.

Obviously, the reverse movement of the motor will begin at reduced speed and the rheostat 108 will remain cut out of the motor circuit as long as contact R'' remains in engagement with either of the contacts R or R'. However, as soon as the continued reverse movement of the carriage carries contact R'' out of said engagement, full current will again be available in the motor circuit.

It will be clear that the driving mechanism hereinabove described and illustrated in the drawings provides a compact and reliable means for driving the carriage of a knitting machine and is measurably more simple and effective than purely mechanical means heretofore designed and used for a similar purpose.

I claim as my invention:

1. A motor control system comprising a motor, current control means in the circuit of said motor including a reversing switch and variable resistance, a relay for actuating the switch and a relay for varying the resistance in the motor circuit, both of said relays being in the same circuit, and means for alternately opening and closing said relay circuit.
2. A motor control system comprising a motor, current control means in the circuit of said motor including a reversing switch and variable resistance, a slow acting relay

for actuating the reversing switch and a relatively more rapidly acting relay for varying the resistance in the motor circuit, both of said relays being in the same relay circuit, and means for energizing the magnets of said relays simultaneously.

3. The combination with a reciprocating member and a motor for driving the same, of a reversing switch in the motor circuit, means for actuating said reversing switch and means in circuit with said actuating means to reduce the speed of the motor prior to effective operation of said means for actuating the reversing switch.

4. In a motor control system for knitting machines, the combination of a reciprocating carriage carrying a contact, a fixed contact at one end of the run of the carriage and a slidably adjustable contact at the opposite end of the run of the carriage, said fixed and slidably adjustable contacts being arranged to alternately engage the contact on the carriage, driving means for said carriage including a motor operatively connected with the carriage, and a reversing switch in the motor circuit, and a switch actuating relay in circuit with the aforesaid contacts and operable to actuate the reversing switch upon engagement of the carriage contact with either of the other contacts.

5. In a motor control system for knitting machines, the combination of a reciprocating carriage carrying a contact, a fixed contact at one end of the run of the carriage and a slidably adjustable contact at the opposite end of the run of the carriage, said fixed and slidably adjustable contacts being arranged to alternately engage the contact on the carriage to close a relay circuit, a carriage driving motor, and motor speed varying means including a relay in said circuit operative during engagement of the carriage contact with either of the other contacts.

6. In a motor control system for knitting machines, the combination of a reciprocating carriage carrying a contact, a fixed contact at one end of the run of the carriage and a slidably adjustable contact at the opposite end of the run of the carriage, said fixed and slidably adjustable contacts being arranged to alternately engage the contact on the carriage, driving means for said carriage including a motor operatively connected with the carriage, a reversing switch in the motor circuit, motor speed changing means, and means in circuit with the motor speed changing means to actuate the reversing switch upon engagement of the carriage contact with either of the other contacts.

In testimony whereof, I have signed my name to this specification this 13th day of July 1921.

WILLIAM FELS.
